(57) **CLAIM**

I claim the ornamental design for a wire basket, as shown and described.

DESCRIPTION

FIG. 1 is a top, front, left side perspective view of a wire basket showing my new design;

FIG. 2 is a top, rear, left side perspective view thereof; FIG. 3 is a left side elevational view thereof; the right side elevational view being a mirror image of the left side elevational view;

FIG. 4 is a top plan view thereof;

FIG. 5 is a bottom plan view thereof;

FIG. 6 is a front elevational view thereof; and,

FIG. 7 is a rear elevational view thereof.

The broken lines shown in the figures represent portions of the wire basket that form no part of the claimed design.
